UNITED STATES PATENT OFFICE.

CONRAD M. CONRADSON AND PRENTICE CONRADSON, OF MADISON, WISCONSIN.

PAPER TOWEL.

1,384,515.

Specification of Letters Patent. Patented July 12, 1921.

Application filed July 6, 1920. Serial No. 394,093.

To all whom it may concern:

Be it known that we, CONRAD M. CONRADSON and PRENTICE CONRADSON, citizens of the United States, residing at Madison, in the 5 county of Dane and State of Wisconsin, have invented certain new and useful Improvements in Paper Towels, of which the following is a specification.

The object of our invention is to provide 10 a paper towel having a multiplicity of rough, broken edges which will rapidly absorb the moisture when the towel is rubbed over the hands or on the face.

The invention consists in a paper towel, 15 as hereinafter described and particularly pointed out in the claims.

In the accompanying drawings forming part of this specification,

Figure 1 is a view of a paper towel embodying our invention,

Fig. 2 is an enlarged detail view of a portion of the towel,

Fig. 3 is an enlarged section.

In the drawing, 2 represents a paper towel 20 provided with a series of elongated perforations 3. These perforations are preferably made in the paper without removing any of the material, leaving ragged fibrous edges which will more readily absorb moisture 25 than the machine-finished surface of the paper. The perforations may be made by dies or rolls, the material being pressed outwardly beyond the plane of the paper sheet and preferably the projecting edges of the 30 perforations alternate on opposite sides of the paper. The perforations may be of any suitable shape, elongated, circular or oval, and they may be made as a step in the paper-towel making operation or they may be 35 made by a separate process.

The perforations may be arranged to cover the entire surface of the sheet or made in

any design or pattern, or the edge of the sheet may be left unperforated or with one or more strengthening bars of the paper 45 across it.

As shown in Fig. 3, the perforations provide a series of rough edges 4 which, when the towel is rubbed over the hands or on the face, will contact with the wet surface and 50 rapidly absorb the moisture. In this way a paper towel may be much more efficient than where the paper presents an unbroken finished surface.

We claim as our invention:

1. As a new article of manufacture, a paper towel having a plurality of openings therein, the edges of said openings being rough and exposed for absorbing the moisture contacting therewith. 55

2. As a new article of manufacture, a paper towel having a plurality of perforations therein, the edges of said perforations being rough and pressed outwardly beyond the plane of the towel to absorb the moisture 65 contacting therewith.

3. As a new article of manufacture, a paper towel having a series of perforations therein, the edges of said perforations being pressed outwardly upon opposite sides of 70 the towel and adapted to rapidly absorb moisture on the hands and face.

4. As a new article of manufacture, a paper towel having a series of elongated slits formed therein in staggered relation, 75 with the edges of said slits pressed outwardly beyond the plane of the towel, said edges being raw and broken for edgewise contact with the skin and the absorption of the moisture thereon.

In witness whereof, we have hereunto set our hands this 30th day of June, 1920.

CONRAD M. CONRADSON.
PRENTICE CONRADSON.
